UNITED STATES PATENT OFFICE.

GUSTAF H. SCHEFSTROM AND OLEF A. ANDERSON, OF MACOMB, ILLINOIS.

ICE-CREEPER.

1,224,217.

Specification of Letters Patent.

Patented May 1, 1917.

Application filed April 22, 1916. Serial No. 98,002.

To all whom it may concern:

Be it known that we, GUSTAF H. SCHEFSTROM and OLEF A. ANDERSON, citizens of the United States, and residents of Macomb, in the county of McDonough and State of Illinois, have invented certain new and useful Improvements in Ice-Creepers, of which the following is a specification.

The present invention relates to new and useful improvements in ice creepers and the like and has for its primary object the provision of an improved type of ice creeper capable of application to various types of shoes regardless of size, shape or material.

Many ice creepers now in use are incapable of application in connection with rubber boots and other footwear and it is therefore one of the principal objects of our invention together with the foregoing to provide an ice creeper which may be applied in position on a rubber boot as well as on the regular leather shoes.

Another object of our invention is to provide an ice creeper of the class described which is adjustable both in length and width to various sizes of shoes, the ice creeper being so constructed as to automatically conform to the shape of the sole of the shoe or boot when applied thereto.

Other objects and advantages to be derived from the use of our improved ice creeper will appear from the following detail description and the claims, taken with an inspection of the accompanying drawings, in which:

Figure 1 is a top plan view of an ice creeper embodying the improvements of our invention;

Fig. 2 is a longitudinal sectional view taken on the line 2-2 of Fig. 1; and

Fig. 3 is an enlarged fragmental perspective view of the connection between the heel and sole sections of our improved ice creeper.

Referring more particularly to the drawings, wherein similar characters of reference designate like and corresponding parts throughout the various views, 1 and 2 designate in their entireties the heel and sole sections of our improved ice creeper. Referring specifically to the heel section the frame is preferably formed of a sheet of metal having the central portion thereof provided with an opening 3 for lightening same, suitable calks 4 being arranged to project from the underface thereof. The

rear free end of the plate 1 is tapered as at 5 and terminates in an upturned portion 6 for engagement with the heel of the wearer. The marginal edges of the plate 60 1 are provided with upwardly extending tongues 7 to which are riveted as at 8 flexible shoe engaging members such as straps 9 and 10 or the like.

The sole section of our improved creeper 65 comprises preferably a pair of arms 11 and 12 hingedly connected by a rivet 13, said rivet having an elongated head 14 for a purpose which will hereinafter appear. The free end portions of the arms 11 and 70 12 are provided with upstanding tongues 15 arranged at an angle relative to the longitudinal axis of said arms and having connected thereto, by means of rivets 16 or the like, fastening means, such as straps 17. 75

The arms 11 and 12 intermediate their ends are connected by means of a pair of links 18, said links being pivotally connected as at 19 and connected with said arms 11 and 12 as at 20. The connecting members 80 19 and 20 preferably form calks and have projecting heads 21.

The heel and sole sections are adjustably connected by means of a link 21 riveted at 22 to said heel section 1 and being provided 85 adjacent the free end thereof with a plurality of transversely arranged elongated apertures 23. As best shown in Fig. 3 the elongated head 14 of the rivet 13 is rigidly carried by the arms 11 and 12 in such a way 90 that said head normally lies approximately coincidental with the longitudinal axis of the creeper. To connect the heel and sole sections the sections are placed relatively at right angles and the head 14 is inserted through one 95 of the apertures 23. When the ice creeper is straightened for application to a boot or shoe the head 14 becomes arranged at right angles to the opening into which the same has been inserted preventing its dislodgment therefrom. The sole section will automatically adjust itself in the shape and size of the wearer's shoe or boot when the fastening straps 17 are applied in position. 100

From the above description taken in connection with the accompanying drawing, it is thought that a clear and comprehensive understanding of the construction, operation and advantages of our invention may be had, and while we have shown and described our invention as embodying a specific structure, we desire that it be under- 105 110

stood that we may make such changes in said structure as do not depart from the spirit and scope of the invention as claimed.

Having thus fully described our invention, what we claim as new and desire to secure by Letters Patent, is:

1. An ice creeper of the class described, including heel and sole sections, connecting means for said heel and sole sections comprising a link having elongated openings therein, said sole section being composed of a pair of arms pivotally connected at one of their ends to the said connecting means, a pair of links, and a plurality of calk members, one of said calk members pivotally connecting the links at one of their ends, the opposite ends being pivotally connected to the said arms intermediate their ends by means of a pair of said calk members for a purpose specified.

2. An ice creeper of the class described, including heel and sole sections, a link hav-

ing one end thereof pivotally connected to the said heel section, the opposite end of the link being provided with a plurality of transverse elongated openings, a rivet, a pair of arms pivotally connected adjacent one of their ends by means of the said rivet, said rivet having an enlarged head adapted to engage in the said openings, the free ends of the arms being provided with upstanding tongues, fastening straps attached to the said tongues, a plurality of calks, and a pair of links pivotally connected adjacent one of their ends by one of the said calks, the opposite ends thereof being pivotally connected to the arms intermediate the ends thereof by means of calk members, the said links providing a supporting means for the toe of the shoe.

In testimony whereof, we affix our signatures hereto.

GUSTAF H. SCHEFSTROM.
OLEF A. ANDERSON.
